STEAM GENERATOR

Filed Aug. 5, 1927

UNITED STATES PATENT OFFICE

WILFRED R. WOOD, OF LONDON, ENGLAND, ASSIGNOR TO INTERNATIONAL COMBUSTION ENGINEERING CORPORATION, OF NEW YORK, N. Y., A CORPORATION OF DELAWARE

STEAM GENERATOR

Application filed August 5, 1927, Serial No. 210,787, and in Great Britain February 14, 1927.

This invention relates to steam generators of the type in which the boiler is furnace shaped, i. e., it is its own furnace whereby the evaporating surfaces are subject to radiant heat and very high capacities are obtainable with relatively small installations.

One of the primary objects of my invention is to introduce fuel and air into such a furnace in an effective manner.

10 Another object of my invention is to ensure effective circulation throughout such a boiler.

A further object is to reduce the losses in combustibles in such an installation to a negligible quantity; and also to burn coarser fuel whereby the cost of fuel preparation is reduced.

How the foregoing together with such other objects and advantages as may herein-after appear, or are incident to my invention, are realized, is illustrated in preferred form in the accompanying drawings, wherein—

Fig. 1 is a vertical section through a boiler installation embodying my invention, with 25 certain of the parts appearing in elevation.

Fig. 2 is a fragmentary section taken substantially on the line 2—2 of Fig. 1, a portion of the view being broken out to condense the figure,

30 Fig. 3 is a fragmentary plan view of a detail of the invention, and

Fig. 4 is a diagrammatic plan view illustrating the manner of introducing fuel to the furnace.

35 Referring now to the drawings, it will be seen that my improved steam generator comprises, in general, a combustion chamber A; a boiler unit B arranged at the rear of the combustion chamber and comprising an up-

40 per steam and water drum 4, a lower water drum 5, and a bank of upright tubes 6 connecting said drums; and burner means C to be hereinafter fully described.

The combustion chamber A comprises side 45 tubular water walls 7 (only one of which appears in the drawings), a front tubular water wall 8, a rear tubular water wall 9 composed of the first row of tubes of the bank of tubes 6, a top or roof tubular water wall 10 and tubes 11 marginal of the bottom of the

combustion space. Suitable sheathing is provided for enclosing the side, front and top water walls.

The side walls 7 comprise a plurality of closely spaced upright tubes, preferably finned, connected at their upper ends into headers 12 and at their lower ends into headers 13. The upper headers 12 are preferably connected to the upper drum 4 of the boiler unit B by means of a plurality of bent tubes 14 and the lower headers 13 may be directly connected into the lower drum 5 of the boiler unit as shown in Fig. 1 at 13a. The front wall 8 comprises a plurality of similarly finned upright tubes, each tube of which is connected at its upper end into a separate header or junction box 15 and at its lower end into a separate header or junction box 16. Each of the upper headers 15 has connected thereto a pair of tubes of the double row of tubes of which the roof wall 10 is composed, and these tubes are connected at their other ends into the upper steam and water drum 4. It is to be noted that I have preferably provided the upper row of tubes of this 75 double row with fins. Each of the lower headers 16 has connected thereto a tube of the double row of tubes which constitute the tubes 11 marginal of the bottom of the combustion space. It will be seen that the headers 16 although closely spaced transversely considered, are spaced sufficiently apart vertically considered as to provide ample space between the tubes 11 so that gravitating particles may pass therebetween to the refuse 80 hoppers 17. The tubes 11 are connected at their ends opposite the headers 16 into the lower drum 5 of the boiler unit C.

From the foregoing it will be seen that each tube of the water screen tubes 11 is provided with an upcomer tube and that each of the upcomer tubes in turn is provided with two upcomer tubes which connect into the upper steam and water drums of the boiler unit B. Thus effective circulation is ensured 90 which is an important consideration in boilers fired in the manner hereinafter appearing.

Pulverized fuel with carrying air is introduced into the combustion chamber A at the lower part thereof by means of the burners 100

C located at each corner of the chamber. I have preferably located two burners at each corner one above the other and they are set so as to deliver the fuel tangentially to a circle having its center in the axial line of the chamber as diagrammatically indicated in Fig. 4. Air, in addition to that introduced at the burners with the fuel, is introduced into the combustion chamber by means of the air nozzles 18 located below the fuel burners, which air nozzles are arranged in like manner to the burners to tangentially deliver their air streams. The air admitted through these burners is preheated as by means of an air heater 19 located in the flue 20, which air heater is provided with an air inlet 21 and an air outlet 22. The air may be caused to pass through the heater in any suitable manner as, for example, by the draught of the flue, or by means of a fan (not shown) or both. A duct 23, preferably branched and extending along each side of the combustion chamber, leads the preheated air from the air heater outlet to the nozzles 18.

25 From the foregoing it will be understood that the fuel streams injected by the burners C in the manner described will be given a violent swirling motion. The air injected by the nozzles 18 is likewise given a violent swirling motion. By so introducing the fuel and air a violently swirling vertical flame is produced, the axis of the vortex being vertical, which flame sweeps and scours the tubes of the water walls hereinbefore mentioned and produces a high rate of heat transmission. By admitting the air injected by the nozzles 18 in the lower part of the combustion chamber and below the point of fuel admission this air lifts the flame whereby heavier fuel can be burned than has heretofore been possible, the air lift holding the heavier particles up and ensuring their complete combustion. The firing of the fuel in the lower part of the furnace chamber puts gravity and the draft to some extent in opposition, in consequence of which the time interval for combustion of any given particle or particles is lengthened which not only makes it possible to burn coarser fuel but also secures complete combustion within the combustion space, reducing the loss of combustibles to a negligible quantity.

55 Admission of air below the burners, in addition to its sustaining feature, provides a body of air for the consumption of any of the fuel particles which tend to sink below the level of fuel introduction.

In order to maintain the aforesaid swirling action throughout the height of the combustion chamber, I have provided additional air nozzles 24 in the upper part of the combustion chamber which are also arranged tangentially in like manner to the burners C. These nozzles are preferably supplied with preheated combustion air under pressure.

Thus violent agitation, mixing and swirling of the fuel and flame stream is ensured in the upper portion of the combustion chamber.

The products of combustion leave the combustion chamber at the upper part thereof and pass over the tubes of the boiler unit B. In this connection it is pointed out that the front row of tubes of the boiler unit are backed by a baffle 25 extending from the lower drum 5 to a point short of the upper drum 4, thus leaving sufficient space above the baffle at 26 for the products of combustion to escape between the tubes of the front row 9. The products of combustion then pass over the bank of tubes 6 to the outlet 27 communicating with the flue 20. Although the temperature of the gases entering the bank of tubes is high, the final exit temperature is lowered by the bank of tubes, the superheater 28 which is located in the flue and by the air heater.

In order to ensure proper water delivery to the lower drum 5 of the boiler unit B, I have provided a baffle 29 for protecting the rear row of tubes of the bank of tubes 6 from the direct heat of the gases of combustion.

I claim:—

1. A boiler furnace comprising upright front, rear, side and top tubular water walls and cross tubes at the bottom, each tube of said cross tubes being connected with a different tube of an upright wall of the boiler furnace and each tube of said upright wall being connected with more than one tube of the top wall, a lower water drum into which said bottom cross tubes are connected, an upper steam and water drum into which the tubes of the top water wall are connected, downflow means connecting said drums and means for introducing pulverized fuel into said boiler furnace.

2. A boiler furnace comprising upright front, rear and side tubular water walls, a top water wall composed of a plurality of rows of water tubes, a plurality of rows of cross tubes at the bottom, each tube of said cross tubes being connected with a different tube of an upright wall, and each tube of said upright wall being connected with a different plurality of tubes of said top wall, a water drum into which said bottom cross tubes are connected, a steam drum into which the tubes of the top water wall are connected, an off-take for the products of combustion and means for introducing fuel to be burned in suspension.

3. A boiler furnace including upright front, rear and side tubular water walls, a top tubular water wall comprising a double row of tubes, cross tubes at the bottom, a header connecting each tube of said cross tubes with a different tube of one of the said upright walls, and a header connecting each

of the last mentioned tubes with a different pair of tubes of said top wall.

4. A boiler furnace including upright front, rear and side tubular water walls, a top tubular water wall comprising a double row of tubes, a double row of cross tubes at the bottom, the tubes of one row being staggered with relation to the tubes of the other row, a header connecting each tube of said cross tubes with a different tube of one of the said upright walls and a header connecting each of the last mentioned tubes with a different pair of tubes of said top wall.

5. A pulverized fuel burning boiler installation comprising in combination a combustion chamber having its front, side and top walls lined with steam evaporating tubes subject to radiant heat substantially throughout their lengths, and having spaced water tubes marginal of its bottom subject to radiant heat, and a boiler unit comprising a bank of tubes and upper and lower drums connected by said tubes, said unit being so disposed that a row of tubes of said bank together with a baffle associated therewith constitute a rear steam evaporating wall of the combustion chamber subject to radiant heat substantially throughout its length, said baffle terminating short of the top of the combustion chamber to provide an outlet for the gaseous products of combustion, other tubes of said bank being subject to the heat of the gaseous products leaving said outlet and still other tubes of said bank being shielded from the heat of the gaseous products of combustion, the aforesaid front, side, top and bottom tubes and the row of tubes constituting the rear wall of the combustion chamber being connected to receive their water from the lower drum of the boiler unit.

6. In combination, a furnace-shaped boiler, means for introducing fuel tangentially into the lower part thereof to be burned in space, and means for introducing air for combustion below the point of fuel introduction in a manner to create an ascending vortical current sweeping the walls of the furnace-shaped boiler.

7. In combination, a furnace-shaped boiler, means for introducing fuel tangentially into the lower part thereof to be burned in space, means for introducing air for combustion below the point of fuel introduction in a manner to create an ascending vortical current sweeping the walls of the furnace-shaped boiler, and means for introducing air above the point of fuel introduction to maintain said vortical current for the length of the fuel and flame stream.

8. In combination, a furnace-shaped boiler, means for introducing fuel tangentially into the lower part thereof to be burned in space, means for tangentially introducing air for combustion below the point of fuel introduc-

tion and means for tangentially introducing air above the point of fuel introduction.

9. In combination, a furnace having an unrestricted combustion chamber formed of upright steam evaporating surfaces, means for introducing fuel tangentially into the lower part thereof to be burned in space, means for tangentially introducing air for combustion below the point of fuel introduction and means for tangentially introducing air above the point of fuel introduction.

10. In combination, a furnace having an unrestricted combustion chamber formed of upright steam evaporating surfaces, steam evaporating surfaces extending across the bottom, and steam evaporating surfaces extending across the top; means for introducing fuel tangentially into the lower part of said combustion chamber; means for tangentially introducing air for combustion below the point of fuel introduction and above said bottom steam evaporating surfaces; and means for tangentially introducing air above the point of fuel introduction and below said top steam evaporating surfaces.

In testimony whereof I have hereunto signed my name.

WILFRED R. WOOD.
